United States Patent Office.

HORATIO B. WEAVER, OF HARTFORD, CONNECTICUT.

Letters Patent No. 96,369, dated November 2, 1869.

IMPROVEMENT IN LOCKS.

The Schedule referred to in these Letters Patent and making part of the same.

To all whom it may concern:

Be it known that I, HORATIO B. WEAVER, of Hartford, in the county of Hartford, in the State of Connecticut, have invented a new and useful Improvement in Locks; and I do hereby declare that the following is a full and exact description thereof, reference being had to the accompanying drawings, and to the letters of reference marked thereon.

The nature of my invention consists in providing, within a lock-case, a disk, connected to a concentric ring by means of a circular connection, marked F in the drawing, said disk and ring being so arranged as to admit of a partial revolution, under certain conditions of their attachments, and providing, within or between the said connected disk and ring, any number of concentric and eccentric rings or tumblers that it may be desirable to employ.

To enable others skilled in the art to make and use my invention, I will proceed to describe its construction and operation.

Figure 1 is a plan of a lock-case, showing the parts of the lock by dotted lines.

Figure 2 is a section of the lock on line 1 2, fig. 3.

Figure 3 is a view of the lock with the cover-plate removed, and shows the parts in their locked position.

Figures 4 and 5 are two views of the disk and connected ring and circular tumblers, marked 1, 2, 3, 4.

A is the case of the lock.

B is the bolt of the lock.

C is one of the fences in the lock.

D is another of the fences in the lock, and both fences are attached to the lock-case.

E is a circular projection from the ring a', as shown in figs. 1, 3, 4, and 5.

F is a connection between the disk a and ring a'.

a is the disk, and a' is the ring, between which are the tumblers 1, 2, 3, 4. One of the tumblers is a concentric ring, while all of the others are eccentric, let the number be more or less.

b is a stud, around which are wire springs f f. One end of each spring rests against the inner side of the lock-case, and the other end of each spring against one of the tumblers, 1, 2, 3, 4.

The office or purpose of these springs is to cause the notches which are in the edges of the tumblers to engage the end of the fence D, as it is by means of this fence D that the bolt B is held in the locked position, through the medium of the circular projection E, the disk a, the ring a', connection F, the tumblers 1, 2, 3, 4, and the springs f f, around the stud b.

C is a pin, inserted in the disk a, and its purpose is

twofold—to receive the turning-motion of the key in the operation of locking and unlocking the bolt, and to prevent the tumblers 1, 2, 3, 4, which have a notch in each one, and resting upon this pin c, from being thrown too far on to the fence D, by the springs f f, which rest against the tumblers opposite to the fence D.

d is a stem to receive the barrel of the key, in the operation of locking and unlocking the bolt B, and is inserted in the centre of disk a.

e is a pin that passes through the ring a' and through the tumblers 1, 2, 3, 4, and also into the disk a. The tumblers are pivoted upon pin e, and are held by it in place.

By referring to the drawing, it will be seen that a recess in the lock of the lock-case is provided for the disk a to turn in, as upon a pivot.

The disk a and ring a', together with the tumblers 1, 2, 3, 4, occupy all the space between the projecting part of the bolt B and the lock of the lock-case, and are then kept in place in the recess referred to between the ends of the fences C and D. At the same time, by the use of the proper key, they—the disk, ring, and tumblers—are free to make the partial revolution in the locking and unlocking the bolt B.

The operation is as follows:

Insert the key through the cover-plate of the lock, on to the stem d. Turn to the right, until the key strikes the pin C, before referred to. At this point, all of the tumblers, 1, 2, 3, 4, will be lifted from their contact with the fence D, but not far enough to engage the fence C. Consequently, the disk a, connection F, ring a', and projection E, being all connected together, are free to, and can be partially rotated in the recess above referred to in the back of the lock-case. As the bolt B is provided with a receptacle for the projection E, the continuous turning of the key will carry back the bolt B. By the use of an improper key, the tumblers would not be properly placed in relation to the fences C and D; consequently the bolt B could not be drawn.

I claim as my invention, and desire to secure by Letters Patent—

The combination of disk a, ring a', connection F, with the circular notched tumblers 1, 2, 3, 4, and the fences C and D, the whole operating together in the manner and for the purpose specified.

HORATIO B. WEAVER.
